COORDINATED CONTROL VALVE

Parke H. Thompson, Millville, N. J.

Application June 23, 1939, Serial No. 280,721

17 Claims. (Cl. 62—127)

This invention relates to a certain new and useful improvement in co-ordinated control valves adapted particularly, though not exclusively, for use in conjunction with refrigerating systems and the like.

My invention has for its primary objects the provision of a valve of the type stated which is compact in size and economical in construction, which as a unitary structure combines all the necessary and essential features for maintaining accurate and precise control over the system in conjunction with which it is installed, which maintains accurate recirculating control of the liquid supply to the refrigerating system responsive to the rate of return flow thereof, which precisely and accurately maintains desired conditions of back-pressure, which separates the returning refrigerant into its liquid and gaseous components for recirculation and return to the compressor, respectively, which may be assembled and fabricated with ease and facility, and which is highly efficient in the performance of its intended functions.

And with the above and other objects in view, my invention resides in the novel features of form, construction, arrangement, and combination of parts presently described and pointed out in the claims.

In the accompanying drawing—

Figure 1 is a longitudinal sectional view of a control valve constructed in accordance with and embodying my present invention;

Figure 2 is a transverse sectional view of the valve, taken approximately along the line 2—2, Figure 1; and

Figure 3 is a diagrammatic view illustrating the valve in operative association with a refrigerating system.

Referring now in more detail and by reference characters to the drawing, which illustrates a preferred embodiment of my invention, the control valve, generally designated A, comprises a suitably elongated open-end tubular or cylindrical shell 1 constructed preferably of metal and exteriorly provided adjacent its upper end margin with an annular attachment flange 2 having an annular series of spaced threaded apertures 2' for retentively receiving stud-bolts 3 disposed through apertures 3' in a centrally apertured end-plate 4 disposed flatwise over the one or upper end of the shell 1 and sealed upon the ring 2 by means of a suitable gasket 4'.

Adjacent its upper end, the shell 1 is transversely pierced and provided with an annular flange 5 for hermetically sealed threaded en-

gagement with a seating sleeve 6 of a back-pressure regulator r including a housing 7. Peripherally secured in and extending transversely across the housing 7, is a diaphragm 8 provided upon its outer face with an external pressure plate 9 held in concentrically aligned, laterally shiftable position by a ring 10 and biased by a compression spring 11 abuttingly seated at its outer end within a dished spring-retaining washer 12 rotatively mounted on a pin-like projecting end 13 of an adjustment screw 14 threadedly mounted in and projecting through the outer end wall 15 of the housing 7 and provided on its outer end with a cap nut 16, all as best seen in Figure 1 and for purposes presently fully appearing.

Centrally of its inner face, the diaphragm 8 is provided with an internal pressure plate 17 positioned and counter-biased by an annular spring 18 and provided with a preferably integrally formed tubular extension 19 projecting axially inwardly through, and being preferably of rectangular cross-section with a diagonal dimension substantially equal to the diametral size of, the housing sleeve or coupling 6, the extension 19 having a transverse end wall 20 for abutting engagement with an axially projecting valve pin 21, also as best seen in Figure 1 and for purposes presently appearing.

30 Welded or otherwise permanently fixed in the end wall 4, is a tubular member 22 axially bored or machined in the provision of an inwardly converging Venturi neck or diffuser 23 tapering into a more or less straight sided throat or constriction 24 and at its inner end being flared sharply outwardly, as at 25, in the provision of a valve seat 26. The member 22 is further provided in its outer face with an axially extending slot 27 opening at one end upon the oblique face 25 35 and terminating a short distance from the wall 20 and terminating a short distance from the wall 20 engaging end of the member 22, all as best seen in Figure 1 and for purposes presently fully appearing.

40 Formed preferably integrally with the member 22 and extending radially inwardly partially across the Venturi throat 23, is a substantially rigid supporting boss 28 provided at its outer end with a somewhat egg-shaped or streamlined enlargement 29 having a bore 30 in co-axial alignment with the constriction 24. The boss 28 and the body of the insert 22 are provided with intersecting drill holes 31, 32, conventionally plugged, as at 33 and 34, in the provision of normally closed passages, the drill hole 32 at its inner end and in its outer side wall being

provided with an aperture 35 for receiving an annular pilot valve seat 36 positioned for seating co-operation with the pointed end of the valve pin 21.

Welded or otherwise permanently fixed in the bore 30 and extending inwardly through and projecting a substantial distance beyond the constriction 24, is a tubular stem 31 having an aperture 38 for communication with the drill-hole 31 and having in its outer end a nozzle-shaped tip member 39 externally contoured as a continuation of the streamlining end enlargement 29 and provided with an axially extending relief bore 40 of relatively small diameter, all as best seen in Figure 1 and for purposes presently fully appearing.

Shiftably mounted on the stem 31, is a seat-supporting sleeve 41 having a longitudinal vent slot 41' opening on the downstream side of the Venturi throat 24. The sleeve 41 is positioned for extension through and beyond the constriction 24 and provided at its projecting end with an annular cup-like collar 42 having a bottom wall 43 provided with an outwardly projecting annular shoulder 44 and an opposed end face 45 having a short retention flange 46 for engagement with an annular valve plug 47 sized for valve closing co-operation with the valve seat 26, the exposed faces of the sleeve 41, the valve plug 47, and the collar 42 being of somewhat 30 paraboloidal or streamlined shape, all as best seen in Figure 1 and for purposes presently fully appearing.

Welded or otherwise hermetically secured upon the inwardly presented transverse face 48 of the collar 42, is a cylindrical bellows or Sylphon 49 provided at its other end with an inwardly depressed frusto-conical washer 50 having a hub portion 51 welded or otherwise permanently fixed to the tubular stem 31 adjacent its outer end, the portion 51 being diametrically reduced along its outer face, as at 52, for retentively engaging one end of a compression spring 53, in turn, at its other end seatingly disposed around the shoulder 44 of the collar 42 in the formation of an inner expandible chamber *a*.

Marginally welded or otherwise hermetically secured to, and suitably mortised in, the outer face of the collar 42, is a preferably metallic ovoid capsular bulb 54 having an external contour which is a smoothly curved continuation of the streamlined-shaped collar 42 and valve plug 47 and being along its inner face spaced substantially outwardly from the Sylphon 49, dividing the interior of the valve A into an enclosed expansion chamber *b* and an annular or so-called separation chamber *c*. The bulb 54 extends substantially beyond the end of the stem 31 and is provided with a transversely extending end casting 55 having a centrally disposed tubular guide sleeve 56 internally sized for snug-fitting slidable engagement over the end portion of the stem 31 and having a pair of diametrically opposed radial apertures 57 providing communication between the chamber *b* and the interior of the valve stem 31.

Riveted or otherwise fixed upon the bottom face of the slot 27, is a hairpin spring 58 having a flat leaf 59 embracingly disposed around, and by a dished spring washer 60 resiliently secured to, the pin 21. At its free end, the spring leaf 59 is provided with a pair of spaced parallel inwardly projecting ears 61 having a transversely extending pin 62 for rotatively supporting a roller 63 slidably engaging the outwardly presented

paraboloidal surface of the collar 42, all as best seen in Figure 1 and for purposes presently fully appearing.

Welded or otherwise hermetically sealed upon the outer face of the shell 1 adjacent its upper end and projecting tangentially through the shell wall, is a fitting 64 opening into the annular or separating chamber *c* and provided at its outer end with a flange 65 for conventional connection with an inlet line 66, all as best seen in Figure 2 and for purposes presently fully appearing.

Fixed upon and extending annularly around the lower extremity of the insert member 22, is a tubular baffle 67 diametrically enlarged, as at 68, and provided with a downwardly depending skirt 69 spaced a substantial distance below the plane of the fitting 64 and provided with a plurality of annularly spaced vanes 70 projecting radially outwardly from the skirt 69 and being deflected arcuately downwardly for imparting a whirling movement to the gas liquid mixture passing therethrough, all as best seen in Figures 1 and 2 and for purposes presently fully appearing.

At its lower end, the shell 1 is externally provided with an annular attachment flange or ring 71 provided with a plurality of annularly spaced apertures 71' for retentively receiving stud-bolts 72 disposed through apertures 72' formed in a bottom plate 73 extending transversely across the lower open end of the shell 1 and sealed upon the flange or ring 71 by means of an annular gasket 74.

The plate 73 is centrally provided with an internally threaded aperture 75 for adjustably receiving a valve nozzle 76 having a valve orifice 77. Fixed upon the outer face of the end plate 73 in concentric alignment with the aperture 75, is a connection collar 78 arranged for connection in any conventional manner to a supply line 79.

Welded or otherwise permanently fixed upon the upwardly presented face of the end plate 73 and fitting snugly within the lower portion of the shell 1, is an inner supporting shell 80 provided at its upper end with a horizontally extending base plate 81 provided in its upper face with a recess 82 having a bottom wall 83 provided with a centrally disposed aperture 84. Disposed on the upper face of the base plate 81, is a diaphragm 85, which extends across the recess 82 and is centrally provided with an aperture 86 for embracing engagement around the hub portion 87 of a pressure plate 88 disposed flatwise concentrically upon the upper face of the diaphragm 85.

Also disposed upon the upper face of, and in peripheral registration with, the diaphragm 85, is a cap 89 provided centrally on its under face with a shallow annular recess 90 of relatively large diameter and having a bottom wall 91 centrally apertured, as at 92, and extending in spaced parallel relation above the diaphragm 85 in the formation of a pressure actuating chamber *p*. On its under face, the diaphragm 85 is provided with a concentric pressure plate 93 centrally apertured for snugly embracing the downwardly depending hub portion 87 of the pressure plate 88 and being biased upwardly by an annular spring washer 94 seated around its outer peripheral margin against the side wall of the recess 82. Adjacent its outer peripheral margin, the plate 81 is apertured and provided with a vertically extending tube 95 bent over at its upper end and provided with a restricted port or orifice 96, all as best seen in Figure 1 and for purposes presently fully appearing.

Welded or otherwise suitably fixed upon the under face of the base plate 81, is an elbow tube 97 extending radially inwardly to the center of the shell 1 and bent downwardly in the formation of a longitudinal leg 98 terminating in a plane spaced a short distance from the valve orifice 77 and being interiorly provided with a tubular insert shell 99 axially bored in the provision of a Venturi constriction 100. At its bend, the elbow tube 97 is provided with an aperture 101 for shiftably accommodating a tubular valve stem 102 extending axially downwardly through the Venturi constriction 100 and the orifice 77, the stem 102 at its lower extremity being provided with an annular valve plug 103 for closure-forming or seated engagement within the orifice 77.

At its upper end, the stem 102 projects through the aperture 101 and is mounted in and projects through the hub 87 of the upper pressure plate 88 and the aperture 92 of the cap wall 91. It should be pointed out in this connection that the aperture 92 is of slightly greater diametral size with respect to the projecting end of the valve stem 102, so as to allow for a slight amount of leakage from the chamber p , all as best seen in Figure 1 and for purposes presently fully appearing.

Welded or otherwise permanently fixed at its lower end upon the upper face of the base plate 81 and extending perpendicularly upwardly therefrom, is a channel-shaped upright or supporting post 104 having a pair of opposed flanges 105 preferably integrally connected by a transversely extending web member 106. Mounted in and extending between the flange members 105 adjacent the upper end of the upright 104, is a pintle 107 for swingable engagement with a mounting lug 108 of a float ball 109 substantially smaller in diametral size than the base plate 81, all as best seen in Figures 1 and 2 and for purposes presently fully appearing.

Swingably suspended at its upper end from the mounting lug 108 in outwardly spaced relation to the pintle 107, is a link 110 pivotally connected at its lower extremity to the outer end of an actuating lever 111, in turn, pivotally mounted adjacent its opposite end upon a fulcrum pin 112 supported in a fulcrum plate 113 welded on, and extending horizontally across the upper projecting end of, the valve stem 102, the lever 111 being preferably integrally provided with a horizontally disposed web-portion 114 projecting beyond the fulcrum pin 112 and abuttingly engaging the upper end of a valve pin 115 shiftably mounted in the upper end of the valve stem 102 for co-operation with a tubular seat forming insert 116 welded or otherwise rigidly secured within the valve stem 102.

At its upper end, the valve pin 115 is operably connected with one leg of a small hairpin spring 117 for normally urging the pin 115 upwardly against the web 114 of the actuating lever 111. Just above the upper end of the seat-forming insert 116, the valve stem 102 is provided with a pair of diametrically opposed pilot ports 118 opening into the chamber p , all as best seen in Figure 1 and for purposes presently fully appearing.

The inner shell 80 and the outer shell 1 are further provided with coinciding apertures 119 in registration with the open horizontally disposed end of the bent tube 97 and opening into a connection collar 120 welded or otherwise rigidly secured upon the outer face of the shell 1 for 70 75

connection in any conventional manner to a pipe line 121, all as best seen in Figure 1 and for purposes presently fully appearing.

Welded or otherwise hermetically sealed upon the upper face of the end plate 4 in registration with the mouth of the Venturi throat 23, is a coupling collar 122 for connection in any conventional manner to a return or suction line 123.

Although control valves constructed in accordance with my present invention may be employed in a wide variety of installations, I have for purposes of illustration chosen to describe its use and operation in connection with a refrigerating system including a compressor B, a liquid condenser-receiver C, and a kinetic evaporator D. The valve A is connected through the intake or supply line 79 to the condenser-receiver C and through the return line 123 to the suction or intake side of the compressor B. The pipe line 121 is connected to the intake side of the evaporator D and the return line 66 finally connected to the outlet side of the evaporator D, all as best seen in Figure 3.

Under starting conditions, there will be a relatively small amount of liquid return from the evaporator D; hence, the float ball 109 will drop to its lowest position, swinging the link 110 downwardly and pivoting the actuating lever 111 so as to permit upward shifting movement of the valve pin 115. As the valve pin 115 moves upwardly, a relatively small amount of high pressure refrigerant will flow through the pilot ports 118 into the chamber p , depressing the diaphragm 85 and, at the same time, shifting the valve stem 102 downwardly and moving the valve plug 103 out of seated engagement, thereby permitting a supply of liquid refrigerant to flow upwardly through the Venturi constriction 100 and the elbow tube 97 into the pipe line 121 for delivery to the evaporator D.

The evaporated liquid gaseous refrigerant mixture returning from the evaporator D through the line 66 is forced to pass between the vanes 70 by which it is centrifugally separated into its liquid and gaseous components. The unevaporated liquid refrigerant flows downwardly along the inner side faces of the shell 1 upon and through the port 96 and the tube 95 into the interior of the inner shell 80, whence it is drawn by the Venturi constriction 100 into the elbow tube 97 for recirculation with the incoming fresh refrigerant.

If, at any time, the rate of return flow of liquid refrigerant increases beyond the selected volume which the port 96 has been sized to accommodate, the excess volume of returning refrigerant will build up a substantial head of returned liquid refrigerant above the base plate 81. As the level of this liquid refrigerant rises, the float ball 109 and its associated link 110 will be shifted upwardly, reversely pivoting the actuating lever 111 and shifting the valve pin 115 toward closed position for either restricting or entirely cutting off the supply of high-pressure refrigerant to the chamber p , thereupon permitting the diaphragm 85 to be returned to normal position under the force of the annular spring 94, thereby shifting the valve stem 102 upwardly and throttling or entirely cutting off the flow of fresh liquid refrigerant through the orifice 77.

As long as the temperature of the evaporator D is at or below the desired temperature for which the back-pressure regulator r is set, the annular valve plug 47 will remain in seated position under the force of the tension spring 53.

When, however, the temperature rises materially beyond the desired point, the back-pressure will be sufficiently increased so as to shift the diaphragm 8 and its associated pilot valve pin 21 outwardly, admitting relatively high-pressure gaseous refrigerant to the chamber b and shifting the bulb 54 and its associated annular valve plug 47 downwardly out of seated engagement with the valve seat or orifice 26, and thus permitting the gaseous refrigerant to be exhausted through the suction line 123 and returned to the compressor for liquefaction.

The present valve efficiently accomplishes the objects stated, and it should be pointed out in this connection that the back-pressure regulating mechanism is automatically self-compensating, that is to say, the arcuate face of the ovi-capsular member 54 slides under and shifts the roller 63 varying the degree of flexure in the spring 58 and correspondingly imposing upon the valve pin 21 by the difference between the force of the spring 11 and the pressure on the pressure plate 17, as more particularly and fully described and pointed out in my copending application Serial No. 280,722. In addition, the flow control mechanism is also automatically self-compensating as more particularly and fully disclosed in my copending application Serial No. 280,720. Thus it will be seen that all of the control elements of the present valve are so arranged and constructed that cycling or wild hunting, which results from valve over-travel, is entirely eliminated.

It should be understood that changes and modifications in the form, construction, arrangement, and combination of the several parts of the valve may be made and substituted for those herein shown and described without departing from the nature and principle of my invention.

Having thus described my invention, what I claim and desire to secure by Letters Patent is—

1. A control structure for use in regulating apparatus adapted to receive a supply-flow of liquid and discharge a return flow containing varying proportions of liquid and gas, said structure comprising first valve means, second valve means, means for receiving the return flow and separating the same into liquid and gaseous components, means responsive to the pressure of the gaseous component for actuating the first valve means, and means responsive to the rate of return of the liquid component for actuating the second valve means.

2. A control structure for use in regulating apparatus adapted to receive a supply-flow of liquid and discharge a return flow containing varying proportions of liquid and gas, said structure comprising first valve means, second valve means, means for receiving the return flow and separating the same into liquid and gaseous components, means responsive to the pressure of the gaseous component for actuating the first valve means, means responsive to the rate of return of the liquid component for actuating the second valve means, and means associated with the second valve means for re-inducting the liquid component into the supply flow.

3. A control structure for use in regulating apparatus adapted to receive a supply-flow of liquid and discharge a return flow containing varying proportions of liquid and gas, said structure comprising a chamber, first and second valve means, means within the chamber for receiving the return flow and separating the same into liquid and gaseous components, pilot valve

means responsive to the pressure of the gaseous component for actuating the first valve means whereby to maintain a predetermined pressure within the chamber, means responsive to the rate of return of the liquid component for actuating the second valve means, and means associated with the second valve means for withdrawing the return liquid from the chamber and introducing it into the supply-flow for recirculation.

4. A control structure for use in regulating apparatus adapted to receive a supply-flow of liquid and discharge a return flow containing varying proportions of liquid and gas, said structure comprising a chamber, first and second valve means, means within the chamber for receiving the return flow and separating the same into liquid and gaseous components, pilot valve means responsive to the pressure of the gaseous component for actuating the first valve means, means responsive to the rate of return of the liquid component for actuating the second valve means, and Venturi means associated with the second valve means for withdrawing the return liquid from the chamber and introducing it into the supply-flow for recirculation.

5. A control structure for use in regulating apparatus adapted to receive a supply-flow of liquid and discharge a return flow containing varying proportions of liquid and gas, said structure comprising first valve means, second valve means, means for receiving the return flow and separating the same into liquid and gaseous components, means responsive to the pressure of the gaseous component for actuating the first valve means, means operatively associated with the first valve means for damping the movement of said valve means for substantially preventing over-travel, and means responsive to the rate of return of the liquid component for actuating the second valve means.

6. A control structure for use in regulating apparatus adapted to receive a supply-flow of liquid and discharge a return flow containing varying proportions of liquid and gas, said control device comprising first valve means, second valve means, means for receiving the return flow and separating the same into liquid and gaseous components, means responsive to the pressure of the gaseous component for actuating the first valve means, means responsive to the rate of return of the liquid component for actuating the second valve means, and means operatively associated with the second valve means for damping the movement of said valve means for substantially preventing over-travel.

7. A control structure for use in regulating apparatus adapted to receive a supply-flow of liquid and discharge a return flow containing varying proportions of liquid and gas, said structure comprising first valve means, second valve means, means for receiving the return flow and separating the same into liquid and gaseous components, means responsive to the pressure of the gaseous component for actuating the first valve means, means operatively associated with the first valve means for compensating said valve means against over-travel, means responsive to the rate of return of the liquid component for actuating the second valve means, and means operatively associated with the second valve means for damping the movement of said valve means for substantially preventing over-travel.

8. A unitary control for use with a refrigerating system comprising a tubular shell having

upper and lower end walls respectively provided with outlet and inlet connections, an intermediate transverse member disposed between the end walls for dividing the control into upper and lower chambers, auxiliary inlet means opening to the upper chamber for inducting a return flow of liquid and gas from the refrigeration system into said upper chamber, auxiliary outlet means opening to the lower chamber, a tubular insert mounted co-axially in the upper chamber and internally contoured in the provision of a Venturi constriction, a boss formed integrally with the insert and projecting radially into the diffuser of the Venturi constriction, a tubular valve stem rigidly mounted in the boss and extending axially through the Venturi constriction, a valve plug shiftably mounted on the stem, means mounted on the stem and operatively connected to the plug for forming an expansible chamber around an end of the stem for shifting the plug into and out of seated engagement in the Venturi constriction, said means being in communication with the interior of the valve stem and said stem being, in turn, connected to the upper chamber, pilot valve means operatively associated with the valve stem for controlling the flow of refrigerant to the expansible chamber, a tube disposed in the lower chamber for conducting supply liquid from the inlet connection to the auxiliary outlet means, and secondary valve means actuatable responsive to the rate of return of the liquid component in the return flow entering the upper chamber through the auxiliary inlet in the upper chamber for controlling the flow of liquid through the tube.

9. A unitary control for use with a refrigerating system comprising a tubular shell having upper and lower end walls respectively provided with outlet and inlet connections, an intermediate transverse member disposed between the end walls for dividing the control into upper and lower chambers, auxiliary inlet means opening to the upper chamber for inducting a return flow of liquid and gas from the refrigerating system into said upper chamber, auxiliary outlet means opening to the lower chamber, a tubular insert member mounted co-axially in the upper chamber and internally contoured in the provision of a Venturi constriction, a boss formed integrally with the insert member and projecting radially into the diffuser of the Venturi constriction, a tubular valve stem rigidly mounted in the boss and extending axially through the Venturi constriction, a valve plug shiftably mounted on the stem, means mounted on the stem and operatively connected to the plug for forming an expansible chamber around an end of the stem for shifting the plug into and out of seated engagement in the Venturi constriction, said means being in communication with the interior of the valve stem and said stem being connected to the upper chamber, pilot valve means operatively associated with the valve stem for controlling the flow of refrigerant to the expansible chamber, a tube disposed in the lower chamber for conducting supply liquid from the inlet connection to the auxiliary outlet means, secondary valve means actuatable responsive to the rate of return of the liquid component in the return flow entering the upper chamber through the auxiliary inlet in the upper chamber for controlling the flow of liquid through the tube, means for conducting return liquid from the upper chamber to the lower chamber, and

means for re-inducting said return liquid into the tube.

10. A unitary control for use with a refrigerating system comprising a tubular shell having upper and lower end walls respectively provided with outlet and inlet connections, an intermediate transverse member disposed between the end walls for dividing the control into upper and lower chambers, auxiliary inlet means opening to the upper chamber for inducting a return flow of liquid and gas from the refrigerating system into said upper chamber, auxiliary outlet means opening to the lower chamber, a tubular insert member mounted co-axially in the upper chamber and internally contoured in the provision of a Venturi constriction, a boss formed integrally with the insert member and projecting radially into the diffuser of the Venturi constriction, a tubular valve stem rigidly mounted in the boss and extending axially through the Venturi constriction, a valve plug shiftably mounted on the stem, means mounted on the stem and operatively connected to the plug for forming an expansible chamber around an end of the stem for shifting the plug into and out of seated engagement in the Venturi constriction, said means being in communication with the interior of the valve stem and said stem being connected to the upper chamber, pilot valve means operatively associated with the valve stem for controlling the flow of refrigerant to the expansible chamber, a tube disposed in the lower chamber for conducting supply liquid from the inlet connection to the auxiliary outlet means, secondary valve means actuatable responsive to the rate of return of the liquid component in the return flow entering the upper chamber through the auxiliary inlet in the upper chamber for controlling the flow of liquid through the tube, means for conducting return liquid from the upper chamber to the lower chamber at a relatively constant rate of flow, and means for re-inducting said return liquid into the tube.

11. A control structure for use in regulating apparatus adapted to receive a supply-flow of liquid and discharge a return flow containing varying proportions of liquid and gas, said structure comprising a tubular shell having opposed end walls, an intermediate wall disposed between the shell end walls for dividing the shell into upper and lower chambers, first valve means in the upper chamber for controlling the back-pressure, second valve means in the lower chamber for controlling the supply-flow, and means in the upper chamber for actuating the second valve means responsive to the quantity of liquid in the return flow.

12. A control structure for use in regulating apparatus adapted to receive a supply-flow of liquid and discharge a return flow containing varying proportions of liquid and gas, said structure comprising a tubular shell having opposed end walls, an intermediate wall disposed between the shell end walls for dividing the shell into upper and lower chambers, first valve means in the upper chamber for controlling the back-pressure, means associated with the first valve means for separating the return flow into liquid and gaseous components, second valve means in the lower chamber for controlling the supply-flow, and means in the upper chamber for actuating the second valve means responsive to the quantity of liquid in the return flow.

13. A unitary control for use with a refrigerating system having an evaporator adapted to

receive a supply flow of liquid refrigerant and discharge a return flow of mixed gaseous and liquid refrigerant, said control comprising a tubular shell having transverse closure-forming end walls, an outlet connection mounted centrally of and extending through one of said walls, a tubular insert mounted upon said end wall and extending co-axially into the shell as a continuation of the outlet connection and being open at its inner end for communication with the interior of the shell, a return line connection extending through the shell wall and opening into the annular space between the insert and the shell, centrifugal separator means mounted annularly about the insert for separating the return refrigerant into liquid and gaseous components, a valve plug operably mounted for co-operation with the insert, and pressure-responsive shiftable means operably connected to said plug for shifting the same into and out of seated engagement in the insert responsive to variations in the pressure of the gaseous component.

14. A unitary control for use with a refrigerating system having an evaporator adapted to receive a supply flow of liquid refrigerant and discharge a return flow of mixed gaseous and liquid refrigerant, said control comprising a tubular shell having transverse closure-forming end walls, an outlet connection mounted centrally of and extending through one of said walls, a tubular insert mounted upon said end wall and extending co-axially into the shell as a continuation of the outlet connection and being open at its inner end for communication with the interior of the shell, a return line connection extending through the shell wall and opening into the annular space between the insert and the shell, centrifugal separator means mounted annularly about the insert for separating the return refrigerant into liquid and gaseous components, a valve plug operably mounted for co-operation with the insert, means actuated by the pressure of the gaseous component and operatively connected to said plug for shifting the same into and out of seated engagement in the insert, and pilot valve means responsive to variations in pressure of said gaseous component for controlling the flow of gaseous component to the plug-actuating means.

15. A unitary control for use with a refrigerating system having an evaporator adapted to receive a supply flow of liquid refrigerant and discharge a return flow of mixed gaseous and liquid refrigerant, said control comprising a tubular shell having transverse closure-forming end walls, an outlet connection mounted centrally of and extending through one of said

walls, a tubular insert mounted upon said end wall and extending co-axially into the shell as a continuation of the outlet connection and being open at its inner end for communication with the interior of the shell, a return line connection extending through the shell wall and opening into the annular space between the insert and the shell, centrifugal separator means mounted annularly about the insert for separating the return refrigerant into liquid and gaseous components, a valve plug operably mounted for co-operation with the insert, means actuated by the pressure of the gaseous component and operatively connected to said plug for shifting the same into and out of seated engagement in the insert, pilot valve means responsive to variations in pressure of said gaseous component for controlling the flow of gaseous component to the plug-actuating means, a supply line extending through the shell for conducting a supply of refrigerant to the evaporator, and means in the shell for controlling said flow of supply liquid responsive to the rate of flow of liquid from the separator.

16. A unitary control valve for use with a device adapted to receive a supply flow of fluid and discharge against a given back-pressure a return flow containing a quantity of liquid, said valve comprising back-pressure regulating means, means for abstracting the liquid from the return flow, metering means for measuring the rate of return flow of the abstracted liquid and moving mechanically responsive to variations in such rate of flow, valve means actuatable responsive to movement of said metering means for throttling the supply flow, and means for recirculating such abstracted liquid in an amount which varies as a function of the back-pressure established by the back-pressure regulating means and the rate of supply flow established by the throttling means.

17. A unitary control valve for use with a device adapted to receive a supply of fluid and discharge against any given back-pressure, a return flow of fluid having a liquid component, said valve comprising back-pressure regulating means, means for abstracting the liquid component from the return flow, metering means moved by said liquid component in such a manner that the degree of movement is a measure of the amount of variation in the rate of flow of said liquid component, means actuatable responsive to movement of the metering means for throttling the supply flow and thereby establishing an inlet pressure, and means for recirculating such liquid component in an amount which varies as a function of the back-pressure and the rate of supply flow.
